Inventor:
William D. Coolidge,
by *Alfred Davis*,
His Attorney.

UNITED STATES PATENT OFFICE.

WILLIAM D. COOLIDGE, OF SCHENECTADY, NEW YORK, ASSIGNEE TO GENERAL ELECTRIC COMPANY, A CORPORATION OF NEW YORK.

X-RAY APPARATUS.

1,215,116.

Specification of Letters Patent.

Patented Feb. 6, 1917.

Application filed May 1, 1915, Serial No. 25,150. Renewed October 24, 1916. Serial No. 127,498.

To all whom it may concern:

Be it known that I, WILLIAM D. COOLIDGE, a citizen of the United States, residing at Schenectady, in the county of Schenectady, 5 State of New York, have invented certain new and useful Improvements in X-Ray Apparatus, of which the following is a specification.

The present invention comprises an X-ray 10 device operable to yield a great output of X-rays without overheating and melting the metal on the surface of the electrode subjected to the discharge.

It is well-known that one of the main 15 limitations of X-ray tubes is the fact that the rapid evolution of heat at the focal spot causes the most refractory metals to melt locally even when the target has a large heat-storage capacity. In other words, the 20 upper limit of energy input is the value at which the heating effect of the cathode discharge at the focal spot melts and volatilizes the metal of the target.

In accordance with my invention, an X-ray 25 tube of increased capacity is provided by rotating the tube as a whole and deflecting the cathode beam out of line with the axis of rotation, thus renewing the surface subjected to the discharge while keeping the 30 focal spot fixed in space.

The novel features of my invention will 35 be pointed out with greater particularity in the appended claims, and for a more detailed description of the invention reference 40 may be had to the accompanying drawings in which Figure 1 illustrates one embodiment of my invention partly in perspective and partly in section, and Fig. 2 a top view of the surface of the particular form of 45 anode shown in Fig. 1.

The particular X-ray tube illustrated is 50 of the incandescent cathode type operating with a pure electron discharge as described by me in the *Physical Review* of December, 45 1913. The envelop 1 contains a cathode 2 adapted to be independently heated by passage of current, and an anode 3 consisting of refractory material, preferably tungsten. The cathode is surrounded by a concave focusing ring 4 which so modifies the electrostatic field as to cause the cathode rays to converge upon a spot of relatively small area on the surface of the anode. The tubular extensions 5, 6 of the envelop 1 are 55 inserted in shafts 7, 8, mounted on bearings

9, 10. These bearings are clamped to an insulating base plate 11 which is in turn connected to a shaft 12 surrounding the X-ray tube, consisting of lead glass or other material impervious to X-rays. Electrical 60 connections are maintained to the cathode and anode by slip rings 13, 14, 15, the rings 13 and 14 serving also to convey a heating current to the cathode, which is indicated as being furnished by a battery 16, connected 65 in series with a resistance 17. The high potential current which generates the X-ray producing discharge is supplied through conductors 18 and 19.

As described in the above mentioned article in the *Physical Review* the heating of the cathode to incandescence causes electrons to be emitted which travel under the influence of the impressed electromotive force to the anode. This cathode stream 70 is diverted out of its axial position in the tube by means of a soleiloid 20 supplied with direct current by any suitable source, for example, a battery 21 in series with a resistance 22. The front of the anode 3 is 75 preferably, but not necessarily of the shape of a truncated cone. When the X-ray tube is revolved as by means of a belt 23, operating on a pulley wheel 24, the cathode discharge will be caused to travel in a circular 80 path over the face of the anode while retaining its position in space so that the X-ray emitted may be used for photographic or any other purpose where focusing is desirable. As the metal receiving the 85 cathode discharge is thus constantly renewed the energy capacity of the tube is 90 correspondingly increased.

What I claim as new and desire to secure by Letters Patent of the United States, is:— 95

1. An X-ray apparatus comprising the combination of an X-ray tube containing co-operating electrodes, means for rotating said tube, means for producing therein an X-ray generating cathode discharge, means 100 for deflecting and holding said discharge out of line with the axis of rotation of said tube.

2. An X-ray apparatus comprising the combination of an X-ray tube, electrodes 105 therefor, means for producing between said electrodes an X-ray generating electrical discharge, magnetic means for deflecting said discharge to cause it to impinge on the anode at a point removed from the center 110

of rotation of said anode, and means for rotating said tube, whereby the bombarded area on said anode is renewed.

3. An X-ray apparatus comprising the combination of an X-ray tube containing a cathode and an anode, means for rotating said tube, and means for holding fixed in space the cathode beam to focus on the anode at a point removed from the center of 10 rotation of said anode.

4. The combination of an X-ray device,

comprising a bulb containing a cathode, an anode, means for focusing rays from said cathode on the anode and means for causing motion of said beam of cathode rays in said device relative to the bulb, thereby distributing the heating effect of said rays over an area on the anode greater than the focal spot.

In witness whereof, I have hereunto set my hand this 29th day of April 1915.

WILLIAM D. COOLIDGE.
